UNITED STATES PATENT OFFICE.

MATILDA R. AUBRY SCHWAHN, OF NEW YORK, N. Y.

DESIGN FOR A JAR.

41,702.

Specification for Design.

Patented Aug. 22, 1911.

Application filed March 27, 1911. Serial No. 617,293. Term of patent 7 years.

To all whom it may concern:

Be it known that I, MATILDA R. AUBRY SCHWAHN, a citizen of the United States of America, residing at New York, in the county and State of New York, have invented a certain new, original, and ornamental Design for Jars, of which the following is a specification, reference being had to the accompanying drawing, forming part thereof.

Referring to the drawing, Figure 1 is a side view and Fig. 2 a top view of a jar of my new design.

I claim:

The ornamental design for a jar, as shown. In testimony, that I claim the foregoing as my invention, I have signed my name in presence of two subscribing witnesses.

MATILDA R. AUBRY SCHWAHN.

Witnesses:

JOHN MURTAGH,
